No. 679,918.

E. C. SHEARS.

Patented Aug. 6, 1901.

SHIELD FOR WOUNDS.

(Application filed Aug. 17, 1900.)

(No Model.)

UNITED STATES PATENT OFFICE.

EDWARD CROSSMAN SHEARS, OF LAKOTA, NORTH DAKOTA, ASSIGNOR, BY DIRECT AND MESNE ASSIGNMENTS, TO SPLINT-GATE BANDAGE COMPANY, OF SAME PLACE.

SHIELD FOR WOUNDS.

SPECIFICATION forming part of Letters Patent No. 679,918, dated August 6, 1901.

Application filed August 17, 1900. Serial No. 27,168. (No model.)

To all whom it may concern:

Be it known that I, EDWARD CROSSMAN SHEARS, a citizen of the United States, and a resident of Lakota, in the county of Nelson 5 and State of North Dakota, have invented a new and Improved Shield for Wounds, of which the following is a full, clear, and exact description.

The purpose of the invention is to provide a shield for attachment to a surgical splint or to be used in connection with plaster-of-paris, starch, or other form of bandage or splint for the safe and convenient septic or antiseptic treatment and protection of wounds 15 and injuries, wherever situated on the body, and also for the inclosure, care, and treatment of boils, carbuncles, and the like, as well as fractures and dislocations of the fingers, toes, and other members of the body. 20 The invention consists in the novel construction and combination of the several parts, as will be hereinafter fully set forth, and pointed out in the claims.

Reference is to be had to the accompanying 25 drawings, forming a part of this specification, in which similar characters of reference indicate corresponding parts in all the figures.

Figure 1 is a view showing in perspective two forms of the device, one form being illustrated as applied to the arm of a person between the shoulder and the elbow and the other form of the device being illustrated as applied to fingers of the hand. Fig. 2 is a plan view of the device which is applied to the fingers of the hand, the said device being shown open. Fig. 3 is a transverse section through the form of the device shown in Fig. 2. Fig. 4 is a plan view of that form of the device which is shown applied between the shoulder and elbow, the cover being shown open. Fig. 5 is a vertical section through the form of the device shown in Fig. 4 with the cover open, and Fig. 6 is a perspective view of a modified form of the device shown 45 in the other figures.

In Figs. 4 and 5 I have illustrated in detail that form of the device which is especially adapted for application to fleshy portions of the body, and in this form of the device a

ring-like body A is provided, which is so 50 curved as to fit the surface of the body to which it is to be applied or to the exterior portion of the bandage or splint which is located directly over the wound to be treated. Usually this body portion A is provided with 55 peripheral extensions 10, having slots 13 therein, through which slots may be passed strips of adhesive plaster for the purpose of holding the device firmly upon the surface to which it is to be applied, said adhesive strips 60 being designated as 14.

In connection with the body A a cap or cover B is employed. This cap or cover consists of a ring-like frame 11 and a body 12, which is constructed of a foraminous material, either reticulated or perforated. Usually the said body 12 is made of wire-gauze of fine mesh, and said body is more or less arched outwardly, so as to provide as much room as possible between the body of the cover and 70 the surface to which the device is applied.

It will be understood that when the device is applied to a splint or to a bandage an opening is to be made in the splint or bandage, which opening will expose the wound when 75 desirable. Therefore by opening the cover B the wound is accessible and may be treated as may be found necessary without removing the bandages or the splint unless they absolutely need renewing, thus obviating unnecessary pain or inconvenience to the patient. The cover B may be held firmly on the body A in any suitable or approved manner. Usually said cover B is hinged to the body and is fastened over the opening therein by means 85 of a hook 14, attached to the body and arranged to enter a staple 15 on the cover, as is shown in Figs. 4 and 5.

In Figs. 2 and 3 I have illustrated in detail a form of the device which is particularly 90 adapted to the treatment of injuries to the fingers of a hand. This form of the device comprises two sections C and D, which have a hinged connection. Each of said members C and D consists, preferably, of a longitudinal frame 16 of U-shaped formation and a transverse frame 17, which is connected with the longitudinal frame at the free ends of the 95

latter and inclines in direction of the bow portion of the said longitudinal frame, and a body portion 18, which is preferably made from fine wire-gauze, and this body portion 5 is also U-shaped in cross-section. Where the body portion connects with the bow-section of the longitudinal frame 16 the body portion may be strengthened by a strip 19, if so desired. The two sections C and D are adapted 10 to close one against the other, and these sections may be made of such size that collectively they will surround one or more of the fingers of the hand, as shown in Fig. 1, or surround a bandage that has been wrapped 15 around the fingers. In this case an opening may be made in the bandage at that portion over the wound, and by separating the members C and D the wound may be readily reached and treated as found necessary.

20 At the inner or open ends of the members or sections C and D of the finger-protective device (illustrated in Figs. 2 and 3) staples 20 are formed upon one of the members of the longitudinal frames 16, and a tape or 25 string 21 is passed through these staples 20 to facilitate fastening the device at the wrist, as shown in Fig. 1. The two members or sections C and D may be secured together in any suitable or approved manner—as, for example, by placing a hook 22 upon one member or section adapted to engage with a keeper 30 on the opposing section.

In Fig. 6 I have illustrated a slight deviation from the forms of the device heretofore 35 described to the extent that the body of the device consists of a suitably-formed shield 24, having an opening 25 therein, and means for attachment to a bandage or splint or for attachment to that portion of the body surrounding 40 the surface at which the wound occurs. The opening 25 in the shield is adapted to be exposed or to be closed by a cover suitably shaped, which cover comprises a frame 26, hinged to the shield, and a body portion 27, 45 attached to the cover and made from gauze or a like material. The cover may be secured upon the shield in any suitable manner—for example, through the medium of hooks 28, carried by the shield and adapted for engagement 50 with keepers 29, located on the cover.

These devices are intended as a valuable addition to every practitioner's armamentarium, and through their use it will be found that certain injuries and wounds may be 55 more conveniently treated and better dressed than where appliances are used without the employment of the devices described. The elements of cleanliness, lightness, and strength have all been embodied in the construction 60 of the improved devices, rendering them in no sense burdensome, but a distinct gain in comfort over other devices.

I desire it to be understood that the frames or body portions of the devices are preferably 65 made of aluminium or other light material suitable for such use, so that the devices in their entirety may be readily sterilized and

will not be undesirably affected by any of the agents employed to cleanse and dress 70 wounds.

The shield facilitates the dressing of wounds of the extremities, since by means of a fenestrum easily and quickly made in any splint, plaster-of-paris, or otherwise the wound may be directly exposed and dressed as often as 75 required without removing the entire splint or the bandages, thus causing the patient no pain or nervous shock and placing the wound in the best condition for repair. Continuous 80 irrigation may be easily kept up, and at the same time the splint or splints will be in position affording assurance to the surgeon that fractures will be kept in apposition. Should a dry dressing be determined upon, it may also be applied easily and quickly by opening 85 the cover of the gate applied to the fenestrum in the splint and after the medicament has been applied to the wound placing in position the gauze or cotton needed. By then closing the cover all the dressing beneath said cover will 90 be retained in proper position. More dressings may be placed upon the upper surface of the cover and bandaged on in order to insure non-contamination from the air.

The finger-splint or protective device will 95 be found exceedingly valuable as a substitute for a splint and also as a means of retaining dressings applied to the fingers, affording also a convenient means for inspecting the parts without disturbance to them.

Having thus described my invention, I claim as new and desire to secure by Letters Patent—

1. A shield for wounds, comprising two skeleton frames hinged together and constructed to fit around and over a wound when closed one upon the other, said shield having a foraminous covering and provided with apertured projections through which a flexible securing-strip is adapted to be passed, 105 substantially as herein shown and described.

2. A shield for wounds, comprising a rigid frame having an opening therein and adapted to be placed over a wound or an opening in the dressing therefor, said frame being provided with means whereby it may be secured in position, a second rigid frame hinged to the first frame and having an opening covered with reticulated material, and means for locking the frames together, substantially as 115 described.

3. A shield for wounds, comprising two ring-like hinged frames having means for locking them together, one of the frames being provided with slotted peripheral projections and the other with a reticulating covering, substantially as described.

In testimony whereof I have signed my name to this specification in the presence of two subscribing witnesses.

EDWARD CROSSMAN SHEARS.
